UNITED STATES PATENT OFFICE

1,941,607

CIGARETTE EXTINGUISHER AND
ASH TRAY

Harry J. Lebherz, Frederick, Md., assignor to
The Everedy Company, Frederick, Md., a corporation of Maryland

Application November 25, 1932
Serial No. 644,348

12 Claims. (Cl. 131—51)

My invention relates broadly to smokers' appliances and more particularly to a construction of cigarette extinguisher and ash tray.

One of the objects of my invention is to provide

5 a simplified construction of cigarette extinguisher and ash tray which is simple in its manufacture and production and effective and convenient in operation.

Another object of my invention is to provide 10 a construction of cigarette extinguisher and ash tray by which the stub of a lighted cigarette may be readily extinguished and the stub ejected into an ash tray without touching the stub after it has been placed in the extinguisher.

15 Still another object of my invention is to provide a construction of cigarette extinguisher and ash tray having means for receiving the burning stub of a cigarette and extinguishing the stub by a smothering operation, with means for automatically ejecting the stub into an ash tray.

A further object of my invention is to provide 20 a simplified construction of cigarette extinguisher and ash tray by which the lighted end of the cigarette stub may be deposited into an open port 25 in the extinguisher casing and the casing automatically closed to atmosphere for effectively smothering the lighted cigarette by the consequent cut off in the supply of oxygen and automatically ejecting the stub of a cigarette previously inserted in the opposite port in the casing.

30 Other and further objects of my invention reside in the construction of cigarette extinguisher and ash tray as will be understood from the specification hereinafter following by reference 35 to the accompanying drawings, in which:

Figure 1 is a top plan view of the cigarette extinguisher and ash tray constructed in accordance with my invention; Fig. 2 is a vertical longitudinal sectional view on line 2—2 of Fig. 1; Fig. 3 40 is a horizontal sectional view on line 3—3 of Fig. 4; Fig. 4 is a longitudinal sectional view of the device, with the casing being shown in section; Fig. 5 is a central vertical longitudinal sectional view of the cigarette extinguisher and ash tray 45 constructed in accordance with my invention taken on line 5—5 of Fig. 3; Fig. 6 is a transverse vertical sectional view taken on line 6—6 of Fig. 5; Fig. 7 is a transverse vertical sectional view taken on line 7—7 of Fig. 5; Fig. 8 is a top plan 50 view of a modified form of the base used in connection with my improved cigarette extinguisher and ash tray; Fig. 9 is a horizontal sectional view of a modified form taken on line 9—9 of Fig. 11; Fig. 10 is a transverse vertical sectional view on 55 line 10—10 of Fig. 11; Fig. 11 is a central vertical

longitudinal sectional view on line 11—11 of Fig. 9; Fig. 12 is a transverse vertical sectional view taken on line 12—12 of Fig. 11; Fig. 13 is another modified form of my invention, showing a central vertical longitudinal sectional view, the casing 60 only being shown in section; Fig. 14 is a central vertical longitudinal sectional view taken on line 14—14 of Fig. 15; Fig. 15 is a horizontal sectional view taken on line 15—15 of Fig. 13; Fig. 16 is a transverse vertical sectional view taken on line 16—16 of Fig. 13; Fig. 17 is a transverse sectional view taken on line 17—17 of Fig. 13; Fig. 18 is another modification of my improved cigarette extinguisher and ash tray showing a vertical longitudinal sectional view taken on line 18—18 of 70 Fig. 19; Fig. 19 is a horizontal sectional view taken on line 19—19 of Fig. 18; Fig. 20 is a transverse vertical sectional view taken on line 20—20 of Fig. 18; and Fig. 21 is a fragmentary sectional view of a modified form of one of the ash deflecting hoods 75 used in connection with my invention.

In illustrating the several embodiments of my invention the drawings have not been made to scale but are to be considered merely as illustrating the arrangement of parts of the mechanism of my invention. I provide a cigarette extinguisher which includes a removable casing detachably secured to an ash tray and which provides an air tight enclosure in which an automatic device for controlling the sealed off condition of the air tight enclosure is mounted. The mechanism includes a pivoted plate member carrying means for closing either of two ports in the casing through which the lighted stub of a cigarette may be projected. The movable 80 plate carries means for deflecting ashes from the lighted stub of the cigarette immediately below one of the ports and means for sealing the other of the ports to atmosphere. Upon the insertion of the lighted stub of the cigarette in one of the ports ashes are deflected from the end of the cigarette and the casing is sealed to atmosphere. The lighted stub of the cigarette is extinguished by a smothering action due to the exclusion of oxygen from the interior of the casing. Upon the insertion of the stub of another cigarette in the other port of the casing, the stub which has been extinguished is ejected automatically and falls into the ash tray. When the casing has become filled with ashes the casing can be readily removed and the ashes deposited from the ash tray.

Referring to the drawings in more detail, reference character 1 designates an ash tray of any suitable form in the center of which I provide 110

suitable attaching means for the cigarette extinguisher. I have shown a raised boss 2 at the center of the tray which is apertured for the passage of a rivet member 3. Rivet member 3 provides securing means for the supporting element 4. The supporting element 4 is provided with a pair of side portions 4a and 4b which project vertically and form journals for the transversely extending shaft member 5. The shaft member 5 provides pivot means for the angularly movable strip 6. The angularly movable strip 6 has downwardly depending side portions 6a and 6b through which the pin 5 extends, thus providing a means for controlling the rocking movement of the angularly movable strip 6. The angularly movable strip 6 has a pair of end portions 7 and 8 extending at acute angles to the plane of the central portion of the strip 6. In each of the end portions 7 and 8 there is an upstruck frusto-conical projection at 9 and 10, respectively. The upstruck frusto-conical projections are so located in the end portions 7 and 8 of strip 6 that they are centered immediately below the ports 11 and 12 respectively in the removable casing 14.

The enclosing casing 14 has opposite side walls instruck at 14a and 14b to provide resilient means beneath opposite sides of the supporting member 4. The walls of the enclosing casing 14 are sufficiently resilient to spring into locked engagement with the supporting member 4. In order to further insure the arrangement of casing 14 over the cigarette extinguisher, I provide upstanding resilient lugs 4c and 4d on opposite ends of supporting member 4 for engaging the interior of the opposite end walls of the enclosing casing 14. The ports 11 and 12 of casing 14 have their interior edges projecting inwardly to abut with the frusto-conical projections 9 and 10 on the ends 7 and 8 of the angularly movable strip 6 and provide a sealed connection therewith. As illustrated in Figs. 1, 2, 4 and 5, the lighted stub of a cigarette, indicated at 15, has been projected into the port 11 in the enclosing casing 14. The action resulting from the projection of the stub 15 to port 11 is that the end 7 carrying the frusto-conical projection 9 is thrust downwardly and thus serves to deflect ashes from the lighted end of the cigarette, distributing such ashes through the interior of the casing; while the other end 8 carrying the frusto-conical projection 10 is thrust inwardly and establishes a sealing connection with the inwardly projecting annular edge of port 12 in casing 14, simultaneously ejecting another stub previously inserted, which stub is caught in tray 1 as indicated at 15a. The interior casing 14 is thus shielded to atmosphere and the stub of the cigarette is forced to smother. The burning end of the cigarette is extinguished by lack of oxygen within the interior of casing 14 for supporting combustion. Fig. 2 illustrates the manner of inserting the lighted stub into the cigarette extinguisher. It is not necessary to again touch the lighted stub, for the insertion of the next succeeding stub at 16 in port 12 operates to thrust the frusto-conical portion 10 of angularly movable strip 6 downwardly, thus distributing ashes from the end of the lighted stub and ejecting the previously inserted stub 16, now extinguished by reason of the movement of the frusto-conical portion 9 upwardly to a position sealing the port 11. The ejected stub 15 falls into the ash tray in a position illustrated generally at 15a in Fig. 75 1 while the stub 16 is smothered within the cas-

ing 14 in a manner similar to the previous action to which stub 15 was subjected.

Figs. 9, 10, 11 and 12 show a modified form of the cigarette extinguisher of my invention. In this arrangement, provision is made for the thrust of the ash deflectors and port sealing devices in parallel plates to avoid any tendency of choking the ports by the clogging of a cigarette stub in the ports during the ejection process. In the form of the invention illustrated in Figs. 9—12, I provide a base support consisting of a strip member 17 having central upstanding side members 17a and 17b thereon. The base 17 also has lugs 17c, 17d, 17e and 17f at diametrically opposite positions thereon for engaging the side walls of the enclosing casing 14. The upstanding lugs 17a and 17b provide supporting members for pintles 18 and 19 which are suitably secured therein. I provide a pantograph construction formed by a pair of parallel levers 20, each of which are journaled centrally on pintles 18 and 19. The levers 20 are pivotally connected at spaced intervals on the stem members 21 and 22 which project from beneath the deflecting plates 23 and 24. The deflecting plates 23 and 24 move in parallel planes with respect to the lower edges of the ports 11 and 12 in the casing 14. That is, the pantograph arrangement is such that a downward thrust of deflecting plate 23 by the insertion of cigarette stub 15 in port 11 operates to shift deflecting plate 23 downwardly in planes parallel to the lower angular edge of port 11 while deflecting plate 24 is raised in parallel planes to a position sealing the lower angular edge of port 12.

Where requirements of production economies make it necessary, I may eliminate the pantograph construction illustrated in Figs. 9—12, and employ the simplified construction illustrated in Figs. 13—17. In this arrangement, the base member 17 has, in addition to the lugs described in connection with Figs. 9—12, two upwardly extending cylindrical wells illustrated at 25 and 26. The deflecting plates 23 and 24 are provided with downwardly extending cylindrical portions terminating into a plurality of guide fingers, adapted to fit within the upwardly extending wells 25 and 26. These fingers effectively prevent the deflecting plates 23 and 24 from tipping to one side during the movement thereof. A balanced lever 27 is pivoted at 27a between upstanding lugs 17a and 17b and carries, by means of yokes 27b and 27c through pivotal connections, the depending cylindrical guides and tongues 23a and 24a. As the cigarette stub 15 is projected into port 11, the deflecting plate 23 is thrust downwardly and is maintained in a position parallel to the lower angular edge of port 11 by means of the guide 25. Simultaneously deflecting plate 24 is projected up vertically in parallel planes to a position sealing the annular depending edge of port 12, and this ejects a cigarette, previously inserted, into the ash tray, the parallel relationship being maintained by concentric movement of the cylindrical member and tongues 24a interiorly of sleeve 26. The guides 25 and 26 serve as sleeves for confining the path of movement of the members 23a and 24a thereby insuring the parallel arrangement of the deflecting plates 23 and 24 with the interior angular seats on ports 11 and 12. The operation of lever 27 is such that a cigarette stub is automatically ejected in one port when a lighted cigarette stub is thrust into the other port.

Where extreme production economies must

prevail, I may employ the construction illustrated in Figs. 18—21. In this arrangement, a base member 28 is riveted or spot welded to the ash tray 1 and is provided with upstanding lugs 28a and 28b at opposite ends thereof to provide engagement means with the opposite interior walls of the enclosing casing 14. A transversely extending plate member 29 projects vertically from the base plate 28 and is provided with recesses 29a and 29b at opposite sides thereof into which the intruded portions 14a and 14b of the opposite side walls of the enclosing casing 14 project and interlock. Plate 29 serves as a fulcrum for balanced lever 30 which is pivotally mounted through the agency of the knife edge recess shown at 30a. Deflecting plates 31 and 32 are carried on the ends of lever 30 and coat with the ports 11 and 12 for alternately sealing the port or ejecting the stub of a cigarette projecting through the port in accordance with the operation of the device as heretofore described. I have shown the position of the balanced lever 30 in full lines in Fig. 18 for the condition which exists when the cigarette stub 15 is projected through port 11 for actuating lever 30, while deflecting plate 32 seals port 12. Dotted line position 30' shows the shifted position of lever 30 when a cigarette stub is projected through port 12, the cigarette stub 15 ejected, and the port 11 sealed.

In Fig. 21 I have shown a slightly modified form of an ash deflecting hood carried by the angularly movable strip, the same being shown as at 40 in the form of a true cone for the purpose set forth.

I have found the cigarette extinguisher and tray of my invention highly practical in its manufacture, production and use, and while I have described my invention in certain preferred embodiments, I desire that it be understood that modifications may be made and that no limitations upon my invention are intended other than are imposed by the scope of the appended claims.

What I claim as new and desire to secure by Letters Patent of the United States is as follows:

1. A smoker's appliance comprising a tray, a cigarette extinguisher mounted on said tray, said extinguisher including an enclosing casing having ports adjacent opposite ends thereof for receiving the stub of a cigarette, and a movable device located within said casing beneath said ports, said movable device being operated by the insertion of one cigarette stub for ejecting a previously inserted cigarette stub from the other of said ports and sealing the enclosing casing to atmosphere.

2. A smoker's appliance comprising a tray, a cigarette extinguisher mounted on said tray, said extinguisher comprising a casing closed to atmosphere, said casing including a pair of ports in the top thereof, a see-saw device pivotally mounted within said casing, deflector plates carried by opposite ends of said see-saw device immediately beneath the ports in said enclosing casing, one of said deflector plates operating to eject the stub of a cigarette projecting through one of said ports and seal said port upon the insertion of the stub of another cigarette through the other of said ports.

3. A cigarette extinguisher comprising an enclosing casing, a pair of ports disposed in said casing, a lever device pivotally mounted within said casing, said lever device supporting the deflector plate adjacent each end thereof in a position immediately beneath the ports in said cas-

ing, one of said deflector plates operating to eject the stub of a cigarette projecting through the port in said casing aligned therewith when a previously inserted cigarette stub is thrust against the other of said deflector plates through the other of the ports aligned therewith.

4. A cigarette extinguisher comprising an enclosing casing having a port adjacent each end of the top thereof, a lever pivotally mounted within said casing, a deflector plate pivotally mounted with respect to each end of said lever, said deflector plates being aligned with the respective ports, one of said deflector plates operating to eject the stub of a cigarette projecting through the port aligned with said deflector plate when the stub of a previously inserted cigarette is thrust through the other of said ports against the deflector plate aligned therewith.

5. A cigarette extinguisher comprising a supporting base, a detachable enclosing casing on said base, said casing having a pair of ports in the top thereof adjacent each end of the casing, a fulcrum device extending from said base centrally of said casing, a lever mechanism pivotally mounted on said fulcrum device, deflector plates carried by each end of said lever mechanism and offset one with respect to the other whereby one of said deflector plates operates to eject the stub of a cigarette projected through the aligned port in said casing and seal said casing to atmosphere when the lighted stub of a previously inserted cigarette is thrust through the other of said ports against the other of said deflector plates.

6. A cigarette extinguisher comprising a substantially airtight casing having a pair of ports in the top thereof adjacent each end of the casing, a see-saw device fulcrumed centrally of said casing, a deflector plate carried by each end of said see-saw device, the deflector plate on one end of said see-saw device operating to eject the stub of a cigarette projected through the port aligned therewith and seal said casing to atmosphere when the stub of another cigarette is thrust through the other of said ports and against the deflector plate aligned therewith.

7. A cigarette extinguisher comprising a support, a detachable airtight casing carried by said support, said casing having a pair of apertures in the top thereof, one of said apertures being adjacent one end of the casing and the other of said apertures being adjacent the opposite end of the casing, a fulcrum device extending from said support, a pantograph mechanism pivotally mounted with respect to said fulcrum device, deflector plates carried by opposite ends of said pantograph mechanism in positions aligned with the apertures in said casing, said deflector plates being offset one with respect to the other whereby one of said deflector plates operates to eject a cigarette stub projecting through one of said apertures and seal said casing to atmosphere when another cigarette stub is thrust through the other of said apertures against the deflector plate aligned therewith for subjecting the last mentioned cigarette stub to a smothering action.

8. A cigarette extinguisher comprising a support, an enclosing casing detachably mounted on said support, said casing having a port adjacent each end of the top thereof, a see-saw device pivotally mounted within said casing, and means carried by each end of said see-saw device and aligned with the ports in said casing for ejecting the stub of a cigarette projecting through

one of said ports and sealing the said port to atmosphere when another lighted cigarette stub is thrust through the other of said ports against the said means carried by the other end of said 5 see-saw device.

9. A cigarette extinguisher comprising a support, an enclosing casing detachably mounted on said support, a standard disposed centrally on said casing and carried by said support, a lever 10 pivoted with respect to said standard, deflector plates pivotally mounted on opposite ends of said lever, means depending from the rear of said deflector plates, guide means carried by said support and slidably engaging the aforesaid means 15 for maintaining said deflector plates in parallel planes in the course of movement thereof with respect to said casing, said casing having ports in the top thereof immediately above said deflector plates, one of said deflector plates operating 20 to eject the stub of a cigarette projected therethrough and seal said casing to atmosphere when the lighted end of another cigarette stub is thrust through the other of said ports against the deflector plate therebetween.
- 25 10. In a cigarette extinguisher, a supporting base, a substantially airtight casing carried by said base, said casing being ported adjacent opposite ends thereof for receiving the stub of a cigarette, and means within said casing operated 30 by the insertion of a cigarette stub through one of said ports for ejecting a previously inserted cigarette stub from another of said ports, said

means operating to seal said casing to atmosphere for subjecting the lighted cigarette stub to a smoldering operation.

11. In a cigarette extinguisher, a support, a casing carried by said support, a pair of apertures in said casing, and means within said casing operated by the thrust of a lighted cigarette stub inserted through one of said apertures for ejecting a previously inserted cigarette stub from the other of said apertures and operating in co-operation with the newly inserted cigarette stub for excluding air from said casing for subjecting the lighted end of the cigarette stub to a smoldering action.

12. A cigarette extinguisher comprising a casing having a pair of apertures in the top thereof adjacent each end of the casing, a guide element disposed beneath each of said apertures, a deflector plate slidably supported in each of said guide elements and movable to opposite limiting positions for sealing said apertures or to a position remote therefrom beneath the top of said casing, and means synchronizing the operation of said deflector plates whereby the thrust of a lighted cigarette stub through one of said apertures against one of said deflector plates operates to eject a previously inserted cigarette stub from the other of said apertures and seal said casing to atmosphere for subjecting the lighted cigarette stub to a smoldering operation.
